Primary Examiner—Louis S. Zarfas*Assistant Examiner*—Eric Watterson*Attorney, Agent, or Firm*—Herbert Dubno**[57]****CLAIM**

The ornamental design for a faucet for a bidet with an extendable spout portion, as shown and described.

DESCRIPTION

FIG. 1 is a top, front, left-side perspective view of a faucet for a bidet with an extendable spout portion showing my new design;

FIG. 2 is a top view thereof;

FIG. 3 is a left side elevational view thereof, the right side being mirror symmetrical thereto;

FIG. 4 is a bottom view thereof;

FIG. 5 is a front view thereof; and,

FIG. 6 is a rear view thereof.
